[57] CLAIM

I claim the ornamental design for a contoured merchandiser, as shown and described.

DESCRIPTION

FIG. 1 is a front elevational view a contoured merchandiser showing my new design;

FIG. 2 is a rear elevational view thereof;

FIG. 3 is a right side elevational view thereof; the left side elevational view is identical but in mirror image;

FIG. 4 is a top plan view thereof; and

FIG. 5 is a bottom plan view thereof;

The broken line showing is for illustrative purposes only and forms no part of the design.

FIG. 6 is a front elevational view of an alternate embodiment of that shown in FIG. 1;

FIG. 7 is a rear elevational view thereof;

FIG. 8 is a right side elevational view thereof; the left side elevational view is identical but in mirror image; and,

FIG. 9 is a bottom plan view thereof.

The top plan not shown of the alternate embodiment is the same that of the first embodiment.
